HYDRAULIC PACKER

Thomas V. Moore, Houston, Tex., assignor to
Standard Oil Development Company, a corpora-
tion of Delaware

Application July 22, 1941, Serial No. 403,543

5 Claims. (Cl. 166—10)

The present invention is directed to a packer for use in conduits and which is especially adaptable for use in the making of drill stem tests.

In carrying out many operations in bore holes it is desirable to form a seal between a string of pipe and the walls of a bore hole. Making a drill stem test is a typical example of such an operation, and in carrying out such a procedure it is usual to form a temporary seal between the drill pipe and the walls of the hole and to open and close valves below the packer by movement of the drill pipe.

An object of the present invention is to provide a packer for use in bore holes.

Another object of the present invention is to provide a hydraulic packer suitable for attachment in a string of pipe which will allow the manipulation of equipment below the packer by rotation of the pipe.

A further object of the present invention is to provide a hydraulic packer having a pressure release valve which will prevent the operating fluid of the packer from exceeding a safe working pressure.

Other objects and advantages of the present invention may be seen from a reading of the following description taken in conjunction with the accompanying drawing in which

Fig. 1 is an elevation showing a packer according to the present invention in a string of pipe within a bore hole;

Fig. 2 is an elevation similar to Fig. 1 with the packer in a string of pipe, but in an expanded state;

Fig. 3 is a cross sectional view of a preferred embodiment of the present invention; and

Fig. 4 is a fragmentary view illustrating a portion of the device shown in Fig. 2 on a larger scale.

Referring specifically to the drawing and first to Fig. 1, packer body 14 which consists essentially of an elastic sleeve of rubber or other suitable material and may be reinforced, if necessary, with longitudinal strips of flexible steel, is attached to upper plunger section 18 by clamp 22 and lower plunger section 19 by clamp 23. This packer assembly is arranged in a string of pipe, the upper plunger section 18 and lower section 19 being secured in the string of pipe 25 by means of conventional tool joints 24.

A detail of a packer clamp and interior arrangement of the packer is shown in Fig. 2. The packer clamp comprises an inner annular section 13 which has its outer surface in the

shape of a frustum of a cone. The inside surface of section 13 is cylindrical and of a size that allows it to fit snugly around the plunger section upon which it is arranged. Packing 16 having a follower 15 attached to section 13 by mating screw threads prevents the escape of fluid between section 13 and the plunger section upon which it is arranged. An outer section 12 fits over the inner section as shown and is secured to head 26 by mating screw threads. In assembling the packer, an end of packer body 14 is slipped inside outer section 12, inner section 13 is slipped inside of this end of the packer and head 26 is then attached to outer section 12. Cap screws 17 in head 26 are then tightened to move inner section 13 relative to outer section 12, thereby clamping the end of the packer.

The upper portions of upper and lower plunger sections 18 and 19 about which the packing 20 sections fit are polished to allow movement of the clamps without the escape of fluid from the interior of the packing body. A collar 24 is secured to lower plunger section 19 by suitable means, such as screw threads, in order to restrain lower packing clamp 23 from downward longitudinal movement with respect to plunger body 19, but leaving it free to rotate about the plunger body. Upper packing clamp 22 is free either to rotate or move longitudinally with respect to plunger section 18.

As will be seen from a study of Fig. 3, the plunger section is in effect a set of jars or an arrangement of telescoping tubing, the sections of which may move longitudinally, but are restrained from rotating with respect to each other. Upper plunger section 18 is tubular in form and provided at its lower end with inwardly projecting shoulder 27. Shoulder 27 is provided with a plurality of longitudinally extending channels 28.

Lower plunger section 19 will usually be constructed as two tubular parts 29 and 30 having the same inside diameter and being attached together by mating screw threads. The upper end of member 29 is provided with outwardly extending shoulder 31 proportioned to fit slidably within upper plunger section 18 and fitted with packing 20 to prevent leakage between the two surfaces. Member 29 is also provided with ribs 32 which slide within channels 28 thereby allowing longitudinal movement between the upper and lower plunger sections, while preventing rotative movement.

The packer assembly may also be provided with a pressure release valve 21, the function of

which is to prevent building up too great a hydraulic pressure on the packer body. The portions of the telescoping tubular members 18 and 19 associated with valve 21 are shown in Fig. 2 and in greater detail in Fig. 4. Release valve 21 may advantageously be mounted on the head of tubular member 29, passages 33 extending through the head of member 29 and passage 34 through shoulder 27 allowing free fluid communication between the release valve and the working fluid in the hydraulic packer.

No specific form of the pressure release valve to be employed has been shown here as there are a number of suitable types which may be used for this purpose. For example, spring loaded release valves are well known for the release of excess pressure from a container and are suitable for this purpose. Other types are also known and may be utilized if desired.

In operation, the plunger section is assembled and the pressure release valve set at a value which will be a safe working pressure for the packer body. The packer body and lower clamp are then placed in position and with the plunger sections in their maximum extended position packer body 14 is filled with an incompressible and preferably viscous liquid 35. The upper clamp is then secured in position and the assembly made up in a string of pipe. The packer is arranged in the pipe at such position that the lower end of the drill pipe will rest on the bottom of the hole when the packer is at the desired level in the bore hole.

The drill pipe with the packer is then lowered into the bore hole until the lower end of the pipe rests on the bottom. Further lowering of the upper end of the pipe causes the plunger sections 18 and 19 to telescope together, this movement increasing the volume of that portion of the plunger body within the packer, displacing liquid 35 to cause the packer body to swell outwardly and seal against the side of the bore hole.

It will be evident that the packer of the present invention has several advantages over those known to the prior art. Some of the outstanding characteristics are: (1) in setting, there is no scraping action of the packer against the walls of the hole, (2) the packer can accommodate itself to holes of irregular shape, and (3) the pressure release valve will prevent the pressure of the working fluid from becoming excessively great.

Although the particular embodiment described is a wall packer, the same principle is applicable to other bore hole tools, such as to rat-hole and other packers. It will also be apparent that various changes in the shape, size and proportion of the several parts of the embodiment shown may be made by a skilled work-

man, and it is my intention that such changes be embraced by the hereto appended claims.

I claim:

1. A packer adapted to be used in bore holes comprising, in combination, a first tubular member, a second tubular member arranged to move longitudinally in said first tubular member, means to prevent fluid leakage between said first and said second tubular members, an elastic sleeve having one end slidably mounted on one of said members and the other end slidably secured to the other tubular member in a fluid-tight manner, and a liquid arranged in the space defined by said sleeve and said tubular members.

2. A device in accordance with claim 1 in which said device is provided with means to prevent relative rotative motion between said tubular members.

3. A packer adapted to be used in boreholes comprising, in combination, a first tubular member, a second tubular member arranged for longitudinal movement in said first tubular member, means to prevent fluid leakage between said first and second tubular members, an elastic sleeve, first and second glands slidably arranged on said first and second tubular members respectively, and clamping means securing one end of said sleeve to the first gland, and the other end of the sleeve to the second gland in a fluid tight manner.

4. In a packer adapted to be used in boreholes, an elastic sleeve and means slidably securing said sleeve to a tubular member including a gland member having a conical outside surface and slidably fitting on said sleeve, a ring member arranged around said gland member with its inside surface slanting in the same direction as the conical surface of said gland and spaced away from said gland to define a passage for receiving an end of said sleeve, and means arranged for biasing the conical surface of said gland member toward the slanting surface of said ring member to secure the sleeve in said passage.

5. In a packer adapted to be used in boreholes, an elastic sleeve, means securing said sleeve to a tubular member including a ring member provided with a conical outside surface slidably arranged on said tubular member, a circumferential groove cut in the inside surface of said sleeve, a packing ring arranged in said groove, a second ring member having a conically shaped inside surface arranged to cooperate with said first ring member to define a passage for receiving an end of said elastic sleeve, and means secured to said second ring member adapted to move the ring members in a direction to diminish the width of said passage.

THOMAS V. MOORE.
